[57] CLAIM

The ornamental design for a combined information and advertising column, as shown and described.

DESCRIPTION

FIG. 1 is a perspective view of a combined information and advertising column showing my new design, with the broken line showing for illustrative purposes only and forming no part of the claimed design;

FIG. 2 is a front elevational view thereof, with the rear being a mirror image; and,

FIG. 3 is a side elevational view thereof, with the opposite side being a mirror image.

FIG. 1

FIG. 2

FIG. 3
